CLAIM

The ornamental design for a USB charging cable with strap, as shown and described.

DESCRIPTION

FIG. 1 is a front elevation view of a USB charging cable with strap, showing my design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a front, top, right, perspective view thereof; and, FIG. 8 is a front, top, right perspective view of the USB charging cable with strap of FIG. 1, shown in an open configuration.

The equal-length broken lines in the drawings depict portions of the USB charging cable with strap that form no part of the claimed design.

1 Claim, 8 Drawing Sheets
